UNITED STATES PATENT OFFICE.

JACOB S. DETRICK, OF BALTIMORE, MARYLAND.

METAL-PLANER.

SPECIFICATION forming part of Letters Patent No. 278,518, dated May 29, 1883.

Application filed November 21, 1882. (No model.)

To all whom it may concern:

Be it known that I, JACOB S. DETRICK, a citizen of the United States of America, residing at Baltimore, in the State of Maryland, have invented certain new and useful Improvements in Metal-Planers, of which the following is a specification, reference being had thereto to the accompanying drawings.

My invention relates to improvements in metal-planing machines, and has for its object to provide a planer adapted to plane pieces of work of greater width than will pass between the side uprights or posts of the ordinary planer.

The machine will first be described, and the invention will then be designated in the claims.

In the annexed drawings, Figure 1 is a side elevation of part of the machine. Fig. 2 is an end elevation. Fig. 3 is a top view of the single side post, cross-beam, and the saddle which moves thereon and carries the tool.

The letter A designates the frame or bed of an ordinary metal-planing machine, resting on the supports A'; B, the reciprocating platen, and c the guides or slides on which the platen moves.

The mechanism for effecting the movement of the platen need not here be particularly described, as the same forms no part of the present invention. It is sufficient to say that the platen may have any desired movement, and any suitable mechanism may be employed to that end.

The letter D designates the single tool-holding post at one side only of the frame. This post is made extra heavy and broad, and in the present instance, in horizontal section, is of an L shape, as shown in Fig. 3, thereby to so distribute the metal as to insure the greatest possible stiffness or rigidity. Instead of the L shape, the post may have any other form which will afford the desired stiffness. The post is supported by a leg or bracket, D', projecting laterally or at a right angle from the frame, and said post is also firmly attached to the side of the frame. The cross-beam E has bearing and is adjustable on the vertical slide or face f of the post, and the slide or face g of the cross-beam is of the same size and shape as that of the post. The saddle I moves on the horizontal face g of the cross-beam, and is fed thereon by suitable mechanism of well-known construction, and which, therefore, need

not here be more fully described. By this construction and combination the cross-beam may be removed, and the saddle removed from the cross-beam and used on the face f of the post, both of which faces the saddle fits with equal accuracy. The movement of the saddle up and down on the post may be effected in the same manner as when on the cross-beam. This is a great advantage upon some kinds of large or special work. A triangular or oblique bracket, L, is attached by one end to the back of the cross-beam, and the other end bears against a vertical slide, h, on the inner side of the broad post. When the cross-beam is moved up or down, the bracket, of course, is carried with it. This bracket, it will be seen, braces the cross-beam, and is an additional means to insure stiffness and steadiness.

The planing-tool is designated by the letter j, and the metal to be planed by the letter k.

A small bracket, n, is bolted to the side of the frame opposite that at which the post is fastened and immediately below the cross-beam, and the end of the cross-beam is provided with a clamping-socket, p. A movable bar, q, has its lower end attached to the bracket, and its upper end passes through the clamping-socket. The bar may be thus employed whenever the size of the work will permit and whenever the character of the work requires special steadiness of the cross-beam. For all general work, however, the single post without the bar will sustain the cross-beam with ample steadiness. The particular clamping-socket shown is not essential. Any suitable means to secure the bar to the end of the cross-beam will suffice. I provide, also, for staying the unsupported end of the cross-beam by means of a rod, r, which is attached to the said end and connected to the end of the frame by a bracket projecting from the side thereof. The stay-rod has thus an inclined position, and a light rod will give great steadiness to the cross-beam. It will be understood that the stay-rod must be adjusted whenever the position of the cross-beam is changed. The advantage of this inclined stay-rod is that while it serves to steady the cross-beam it can often be used without being in the way of a large piece of work, and it may be used whether the oblique bracket is employed or not.

As already stated, the tool-holding post may

have any form which will afford the desired stiffness. I will now add that, instead of one post made heavy and of great breadth, a post consisting of two parts may be employed, both parts being secured at one side only of the frame, and one end of the cross-beam arranged to have bearing on one part, while the oblique bracket has bearing on the other part.

Having described my invention, I claim and desire to secure by Letters Patent of the United States—

1. A metal-planer having attached to the frame on one side only of the reciprocating platen a post to sustain the cross-beam, which said post is L shape in horizontal section, as and for the purpose set forth.

2. A metal-planer having a cross-beam provided with a horizontally-extended oblique bracket, L, and also having attached to the frame on one side only of the platen a post provided with a vertical slide, f, for the adjustment of the cross-beam, and another vertical slide, h, as a bearing for the oblique bracket, as set forth.

3. A metal-planer having attached to the frame on one side only of the platen a post provided with a vertical slide, f, for the adjustment of the cross-beam, a cross-beam having a horizontal slide, g, and a tool-carrying saddle, I, adapted to be used on either slide, as and for the purpose set forth.

4. A metal-planer having attached to the frame on one side only of the platen a post, a cross-beam, one end of which is attached to the post, and a stay-rod, r, connecting the other or unsupported end of the cross-beam with the end of the frame, as and for the purpose set forth.

In testimony whereof I affix my signature, in presence of two witnesses, this 20th day of November, 1882.

JACOB S. DETRICK.
